US00D895624S

(12) **United States Design Patent** (10) **Patent No.:** **US D895,624 S**
(45) **Date of Patent:** **** Sep. 8, 2020**

(54) **CONNECTOR HOUSING**

(71) Applicant: **Adolite Inc.**, Santa Clara, CA (US)

(72) Inventor: **David Liau**, Fremont, CA (US)

(73) Assignee: **ADOLITE INC.**, Santa Clara, CA (US)

(**) Term: **15 Years**

(21) Appl. No.: **29/639,437**

(22) Filed: **Mar. 6, 2018**

(51) LOC (12) Cl. **14-02**

(52) U.S. Cl.

USPC **D14/433**

(57) **CLAIM**

The ornamental design for a connector housing, as shown and described.

DESCRIPTION

FIG. 1 is a top perspective view of a connector housing according to one exemplary embodiment of the present design.

FIG. 2 is a bottom perspective view of the connector housing of FIG. 1.

FIG. 3 is a front view the connector housing of FIG. 1.

FIG. 4 is a back view of the connector housing of FIG. 1.

FIG. 5 is a left side view of the connector housing of FIG. 1.

FIG. 6 is a right side view of the connector housing of FIG. 1.

FIG. 7 is a top view of the connector housing of FIG. 1; and, FIG. 8 is a bottom view of the connector housing of FIG. 1. The broken lines shown are provided for the purpose of illustrating environmental structure and form no part of the claimed design.

1 Claim, 6 Drawing Sheets
